UNITED STATES PATENT OFFICE.

ANTON WILL, OF CHICAGO, ILLINOIS.

COMBINED PHONOGRAPH-CABINET AND TABLE.

1,399,097.

Specification of Letters Patent.

Patented Dec. 6, 1921.

Application filed January 15, 1921. Serial No. 437,495.

To all whom it may concern:

Be it known that I, ANTON WILL, a citizen of the United States of America, residing at Chicago, in the county of Cook and State of Illinois, have invented certain new and useful Improvements in Combined Phonograph-Cabinets and Tables, of which the following is a specification.

This invention relates to certain new and useful improvements in combined phonograph cabinet and table wherein the table top is pivotally mounted upon a supporting frame structure adapted to be swung in a horizontal path to expose the phonograph section of the device.

A further object of the invention resides in the provision of a combined phonograph cabinet and table wherein the phonograph section is disposed beneath the table top adjacent one end of the table with a sliding drawer at the other end thereof, rack compartments for disk records being provided adjacent the phonograph section for housing the records beneath the table top.

A still further object of the invention is to provide a combination article of furniture embodying a phonograph section and a table member, each independently serviceable for the purpose intended and being of the general design of a library table.

With the above and other objects in view, the present invention consists in the novel form, combination and arrangement of parts hereinafter more fully described in connection with the accompanying drawings, and in which like reference characters indicate corresponding parts throughout the several views.

In the drawings,

Figure 1 is a top plan view of the combined phonograph cabinet and table constructed in accordance with the present invention, the table top being moved on its pivotal mounting to expose the phonograph section,

Fig. 2 is an end elevational view of the device with the supporting legs broken away and showing a sliding drawer in one end of the table,

Fig. 3 is a longitudinal sectional view showing the phonograph section and sliding drawer at opposite ends of the device disposed beneath the table top and

Fig. 4 is a cross sectional view taken on line IV-IV of Fig. 3 showing the phono-

graph section with the racks for the record disks.

Referring more in detail to the accompanying drawings, there is illustrated a piece of combination furniture in the form of a combined phonograph cabinet and library table embodying corner supporting legs 1 and a table top 2, the legs being connected by dropped side and end boards 3 and 4 connected to the upper ends 1^a of the table 60 legs by diagonal braces 5 having the ends thereof countersunk in the side and end boards as shown in Fig. 1 with fastening screws 6 securing the diagonal braces to the corner legs, the table frame being of rectangular construction. As shown in Figs. 1 and 4, an upper bead section 2^a is secured to the upper edges of the side and end boards 3 and 4 and upon which the table top 4 is mounted. A bar 7 extends transversely of 75 the device and is anchored at its ends in the side boards 3, the table top 2 being pivotally supported adjacent one end of the bar 7 upon the stud bolt 8 for swinging in a horizontal plane as indicated in Figs. 1 and 3. 80 To limit the swinging movements of the table top in opposite directions, a block 9 shown more clearly in Fig. 1 is secured to the under side of the table top 2 and in the position shown in Fig. 1 engages one side 85 board 3 to limit the opening swinging movement of the table top while the opposite end of the block 9, when the table is moved to its closed position as shown in Fig. 3, engages the adjacent side edge of the transverse bar 90 7 whereby the table top is correctly positioned overlying the table base.

A transverse partition wall 10 extends between the side boards 3 as shown in Figs. 1 and 3 to divide the table structure beneath 95 the table top into separate compartments 11 and 12. The compartment 11 is provided with corner guides 13 for a sliding drawer 14 adapted for moving outwardly of the table as will be evident from an inspection 100 of Figs. 2 and 3.

The compartment 12 of the table constitutes the phonograph cabinet section thereof, said compartment containing a horizontal partition 15 providing a space 16 there- 105 beneath for a motor resting upon the bottom wall 17. A horn member 18 shown in Fig. 3 extends into an apertured block 19 upon the partition 15 with the enlarged outer end 20 thereof extending through the 110

transverse partition 10 and opening at the lower side of the compartment 11. The horizontal partition 15, as shown in Fig. 1 is provided with a central opening 21 for the power shaft of the phonograph motor upon which shaft a disk record turn table may be mounted. The wall 15 supporting the phonograph turn table terminates at points spaced from the side boards 3 as shown in Figs. 1 and 4, the same being mounted on ledges 22 carried by the inner faces of the vertical walls 23 spaced from said side boards to provide record disk racks 24 containing vertical partitions 25. The partitions 24 terminate at points spaced from the adjacent end board 4 and a block 26 is supported at the upper ends thereof having a series of depression pockets 27 therein for containing graphophone needles 20 and the like.

From the above detailed description of the device, it will be readily seen that the applicant has provided a novel construction of combination furniture embodying a phonograph cabinet and a library table, the table top being mounted on a vertical pivot for swinging in horizontal directions to overlie the table structure when the device is in use as a table. When it is desired to use the graphophone, the table top is moved upon its pivot bolt 8 and limited in its swinging movement by the block 9 engaging the bead 2^a as shown in Fig. 1 to expose the phonograph section compartment 12 as

illustrated. The phonograph and its operating motor are disposed within the compartments 12 and 16, the tone arm of the sound box being connected to the block 19 for transmitting sounds to the horn sections 18 and 20. The record disks are conveniently stored in the compartments 24 and separated by the partition racks 25 while the supply of needles are contained within the pockets in the blocks 26.

While there is herein shown and described what is believed to be the preferred embodiment of the invention, it is nevertheless to be understood that minor changes may be made in the form, combination and arrangement of parts without departing from the spirit and scope of the invention as claimed.

What is claimed as new is:

A combined phonograph cabinet and table comprising a table frame, having separate compartments therein with one of said compartments open at its lower side, and a table top hinged to said frame adapted to swing in a horizontal plane to expose one of the compartments, a phonograph horn having the inner end thereof extending into the exposed compartment and the outer end thereof extending into the other compartment and opening at the lower open end of said compartment.

In testimony whereof I affix my signature.

ANTON WILL.
